INTRODUCTION

Watson King,
by Pringle & Dyer, 1850.

United States Patent Office.

WATSON KING, OF SPRINGFIELD, ILLINOIS.

Letters Patent No. 91,640, dated June 22, 1869.

IMPROVEMENT IN HORSE-RAKES.

The Schedule referred to in these Letters Patent and making part of the same.

To all whom it may concern:

Be it known that I, WATSON KING, of Springfield, in the county of Sangamon, and State of Illinois, have invented certain new and useful Improvements in Horse Hay-Rakes; and do hereby declare that the following is a full, clear, and exact description of the same, reference being had to the accompanying drawings, making a part of this specification, in which—

Figure 1 is a plan view of my improved rake;

Figure 2 is a central cross-section on the line x x of fig. 1;

Figure 3 is a detached side elevation of the devices for revolving the axle;

Figure 4 is a top view of the same; and

Figure 5 is a broken longitudinal horizontal section of the axle, showing the manner of securing the teeth therein.

Letters of like name and kind refer to like parts in each of the figures.

My invention relates to a class of horse hay-rakes, in which the teeth are secured to and revolve with the axle; and

It consists, principally, in the means employed for securing said teeth within said axle, and also in the employment and arrangement of the devices for revolving said axle, as is fully set forth hereinafter.

In the annexed drawing—

A represents the axle and rake-head, having pivoted upon either end a wheel, B, of the usual construction.

The shafts C C are secured to said axle by means of a strap, c, passing around the same, so as to allow it to revolve freely within both wheels and straps.

D D, &c., represent the teeth, which are of the usual form, and are each secured to the rake-head or axle A by having their upper ends inserted within a transverse mortise, a, in said axle, and a wedge, d, driven into said mortise, so as to fill the same, and press said tooth firmly against its side.

In order that the teeth may not be accidentally withdrawn, and also to enable them to retain the desired vertical position, the upper end of each is extended through the mortise, and bent to one side, at a right angle, d', so as to fit it to a longitudinal groove, a', intersecting the forward ends of said mortises at a right angle, as shown in fig. 5.

E represents a flanged ratchet-wheel, which is secured to the centre of the axle. A ratchet-bar, F, resting upon and engaging with said wheel, is pivoted at its forward end to a lever, G, which is, in turn, secured to a short shaft, H, working in suitable bearings attached to the foot-board C.

Upon the opposite end of said shaft is a curved handle, I, projecting upward, within convenient reach of the hand, so that by pressing said handle backward, the lever G is carried downward, and forward, and with

it the ratchet-bar F, revolving the ratchet-wheel E and rake-head A, and dumping the hay.

Upon one of the flanges of the ratchet-wheel is an angular tooth, e, projecting upward and forward, which engages with a stop, f, upon one side of the ratchet-bar, said tooth and stop being so adjusted as to prevent the rake-head from revolving when the ratchet-bar is thrown back, and the teeth of the rake are in the desired position for gathering the hay, as otherwise said teeth would be carried backward, and raised from the ground as soon as they commenced gathering the hay.

A rod, X, is secured to the foot-board C, and projecting to the rear, is caused to pass over the ratchet-wheel and bar, and hold the latter in place upon said wheel.

Said rod also serves as a stop to prevent the ratchet-bar from being drawn too far forward, by engaging with a projection, f, upon the end of said bar.

As the revolution of the rake-head, when loaded, would require the expenditure of considerable strength, provision is made for assisting the driver in performing such operation.

A number of holes, x x', is provided in the lever G, by means of which the single-tree is attached thereto, so that the power necessary to draw the rake is applied to the same through said lever.

As will be seen by fig. 2, when the handle I is thrown forward, the lever G projects to the rear, and slightly upward, so as to be nearly on a line with the draught, in which position it is so little affected by the force applied, as to be readily held in position by placing the driver's foot upon the handle; but if said handle be allowed to rise, so as to depress the rear end of said lever below the line of the draught, the power applied through the single-tree will be exerted in such a manner as to still further depress the rear end of said lever, and, by so doing, draw forward the ratchet-bar, and revolve the rake, dumping its load.

It will be observed that when the handle is released, and while the lever G is drawn downward and forward, the forward motion of the wheels must cease, by which means the load is deposited with a certainty and exactness that would be impracticable if said rake were moving forward and revolving at the same time, whereby all scattering of the hay is prevented, and the same neatly placed in windrows, close to which the teeth can commence raking again.

Having thus fully set forth the nature and merits of my invention,

What I claim as new, and desire to secure by Letters Patent, is—

The combined axle and rake-head A, provided with a series of transverse mortises, for the reception of the rake-teeth, and with a longitudinal groove intersecting said mortises, for the reception of the ends of

said teeth, substantially as and for the purpose specified.

Also, the combination of the teeth D, provided with the angular end d', mortise a, groove a', and wedge d, substantially as and for the purpose shown.

Also, the devices for revolving the rake-head, consisting of the ratchet wheel E, ratchet-bar F, lever G, shaft H, and handle I, and in combination therewith, the tooth e upon the flange of the ratchet-wheel, stops f and f', upon the ratchet-bar, and rod z, substantially as shown, and for the purpose described.

Also, combining the draught of the machine with the devices F, G, H, and I, for revolving the rake-head, so that the power applied to move said machine shall operate said rake-head, substantially as and for the purpose shown.

In testimony that I claim the foregoing, I have hereunto set my hand, this 7th day of April, 1869.

WATSON KING.
